UNITED STATES PATENT OFFICE

RALPH B. MOORE, OF PORTLAND, OREGON

TRACTOR HOIST

Application filed July 2, 1927. Serial No. 203,163.

The object of my invention is to provide a novel piece of hoisting or drawing machinery which is quite mobile and which has sufficient power and speed to be effectively used in logging and construction operations.

The standard manner of drawing logs from where they are felled to a central loading station is by means of a logging engine or by animal or mechanical tractive equipment. Logging engines are either mounted upon tracks or upon sleds and are necessarily quite cumbersome and expensive and thus adapted to be used only where large stands of timber are to be logged. On the other hand, the use of tractive equipment is limited by the contour of the logged land and by the time required to traverse the distance between the points of haul.

A large number of isolated stands of timber of limited footage can not be logged economically at the present time by the use of present equipment, and it is the object of my invention to provide power devices to fill this need. Similar conditions are met in construction work at the present time on jobs too large for manual labor and too small or too isolated to use mechanical digger equipment.

I attain this object by mounting upon the rear frame ends of a tractor, preferably of the track-laying type, a two-drum two-speed hoist and connect the operating mechanism therefor to the rearwardly extending power shaft provided for the auxiliary equipment of said tractor. Such shaft is housed and an opening is provided in said housing which is aligned with said shaft, said opening being provided with cover retaining means, and such hoist preferably also is fastened to the tractor through such means.

This type of tractor is usually made "front heavy" so that when a load is being pulled it will not tend to lift the front end of the tractor from the ground, and the operator's position is arranged at the rear of the tractor with the operating controls arranged conveniently about said position.

A further object of my invention is to provide a hoist which is of such weight and is so positioned that it will tend to counteract the

front heavy end of the tractor and to equalize the weight between the two ends to obtain uniform traction, and which hoist is of such size and is so positioned that the operator can view the work being done and can operate the hoist conveniently from his position on the tractor.

A further object of my invention is to mount the hoist at the rear of the tractor in such a manner that it can be operated conveniently, supported securely, and so that the loads imposed thereby upon the tractor can be efficiently resisted.

The details of my invention are hereinafter described in greater detail with reference to the accompanying drawings, in which:

Fig. 1 is a side elevation of a tractor with my improved hoist mounted at the rear end thereof, the hoist being shown in full lines and the remainder of the truck being shown in dotted outline;

Fig. 2 is a fragmentary plan view of the rear end of such tractor with the hoist mounted in place, the rear frame ends and the hoist being shown in full lines and the remainder of the tractor being shown in dotted outline;

Fig. 3 is a fragmentary perspective view of one type of tractor to which my hoist has been applied, this view showing the rear frame ends, housing and the end of the power take-off shaft in full lines, and the remainder in dotted outline;

Fig. 4 is a perspective view of the frame element of the type of tractor shown in Fig. 3;

Fig. 5 is a view similar to Fig. 3 of a modified type of tractor having similar elements and adapted to have my improved hoist mounted thereon;

Fig. 6 is a perspective view of the hoist portion that constitutes a partial housing and supporting element for my improved hoist with the tractor; and

Fig. 7 is a perspective of my improved hoist shown mounted at the rear of a tractor, the latter being shown in dotted outline.

My improved power unit preferably utilizes a tractor *a* of the track laying type as is shown in the drawings in which the controls such as the steering element *a'* and the

like, are grouped at the rear end and adjacent the driver's seat a_2 . The front portion of such tractor is substantially higher than the rear portion so that any appliance or auxiliary device mounted at the front end of such tractor can be viewed from the driver's seat only with great difficulty. Such tractors are uniformly made front heavy so that the draw bar pull will not lift the front end 10 of the tractor from the ground.

My improved hoist b is mounted at the rear of such tractor and is of such size and weight as will approximately counterbalance the front heavy end of the tractor to 15 distribute the weight of the whole evenly upon the treads a_3 of the tractor. Such hoist is preferably of such height that it lies below the horizontal plane of the driver's seat a_2 and that of the controls adjacent 20 thereto and above the plane occupied by the draft connections a_4 . This is for the reason that the operator of the tractor can turn about in his seat and operate the hoist and can easily look over the top of the hoist and 25 view the work being operated upon. Being above the draft connections a_4 , permits the hoist to be used without interference by the draft connections and permits the latter to be used without interference by the hoist. 30 That is, mounting the hoist in this manner permits the tractive power and tractive connections of the tractor to be utilized without restraint and at the same time permits the hoist to be used efficiently.

In tractors of this character, a frame member a_5 extends the full length of the tractor and is the main supporting member for the body of the tractor upon the pivoted tracks a_3 and their supports. The ends of such 40 frame member a_5 extend rearwardly from the tractor, one at each side, and it is to such ends that the draft connections a_4 are usually fastened. Such frame member a_5 comprises two side members which are 45 spaced apart and it is upon these two spaced ends that my improved hoist is supported, in the main.

Above such ends of the frame member a_5 and also extending rearwardly is the stub 50 end of a power take-off shaft a_6 , such end usually being concealed within the transmission housing a_7 and aligned with an aperture in the latter. A removable plate is provided to cover such aperture and bolts or 55 studs a_8 are arranged the latter to hold such plate in place. I remove such plate and use the bolts or studs provided, to fasten my hoist to the transmission housing. The stub end of the power take-off shaft a_6 is arranged 60 substantially in the middle of the transmission housing and above the frame ends and thus the three supporting members for the hoist are arranged approximately in an equilateral triangle and thus 65 constitute a three point support for the hoist.

In Fig. 5 I show a modified type of tractor c in which the frame ends c' and cover supporting means c_2 are also arranged in the form of a triangle, and in addition other openings are arranged at each side of said supporting means c_2 and means c_3 and c_4 are arranged about such openings. In this type of tractor I preferably utilize such latter means also to fasten the hoist to such tractor. In this figure I also show the stub end of 70 the power take-off shaft c_5 and it is to be understood that the operating portions of the hoist are adapted to be fastened to such shaft similarly to the manner, which will hereinafter be described, used to connect the operating elements of the hoist to the shaft c_6 . 75

As is shown most clearly in Figs. 1, 2 and 7, the tracks a_3 extend a substantial distance rearwardly of the transmission housing a_7 and such tracks thus protect the hoist mounted between the same and bolted to the transmission housing. 80

The hoist is driven by the power take-off shaft a_6 which is connected to the power shaft d of the hoist by a coupling e . A combined housing and supporting member f is fastened to the transmission housing a_7 by the bolts of studs a_8 , and is provided with two feet f' which are fastened to the ends of the frame a_5 by bolts g . Formed upon the back of the housing is a bearing f_2 for the shaft d , such bearing being aligned with the power take-off shaft a_6 . Two side pieces h and i are fastened to the housing and supporting member f , and are spaced apart and carry the drums j and k of the hoist between them. 90

A transverse shaft l is journaled in such parts and carries a bevel gear m which meshes with a bevel pinion n on the end of the shaft d . Power is transmitted thru a transmission o to bull gears p . Such transmission and such gears are arranged to make the host a two speed hoist in which the upper drum j runs at a much faster rate than the drum k and thus the drum j is arranged to serve as a trip drum and the drum k as the main drum of the hoist. 105

Clutches, controlled by levers r and s for the drums j and k respectively, control the application of power to the drums and a lever o' adjacent the driver's seat a_2 on the tractor controls the transmission o . A brake for the drums is controlled by a lever t . 110

My improved hoist mounted upon the rear end of a tractor in the manner described, provides a power unit adapted to be used in logging operations as a very portable and sturdy engine. In construction operations such unit can be connected to a drag line bucket and will serve as a very efficient digging machine. Such piece of power equipment thus provided, because of its portability, is able to get into tight places and do 120

quite heavy work, where the cost of putting heavier machines would make the operation prohibitive.

Two speeds permits the work to be done speedily or powerfully and two drums permit a main line and a trip line to be spooled. An operator is able to roll up his cable on the drums in a few minutes and start for another job. The power unit is capable of moving twenty to forty miles in a day on a road and upon arriving at another job, in the same few minutes that it took to roll up the cable, it is ready to go to work. All adjusting of the drums for squaring around for line pulls is done from the driver's seat in a few seconds and the necessity for providing fairleads is eliminated. The use of the tractor as a draft unit is not hampered in the slightest by the mounting of the hoist in the manner described because of the location of the parts relatively to each other.

I claim:

1. In combination with a tractor having two spaced rearwardly extending frame members, a longitudinally-arranged horizontal power take-off shaft terminating at the rearward end of such tractor and arranged above the horizontal plane of such frame ends, such shaft being alined with an aperture in the body of the tractor, cover fastening means arranged adjacent such aperture, a draft connection arranged at the rearward edge of such tractor and below the horizontal plane of such frame ends, an auxiliary hoist of the character described mounted upon the rearward end of such tractor, fastened to the latter by such fastening means adjacent the power take-off shaft aperture and to such frame ends, such hoist being arranged above such frame ends the latter supporting the major portion of such hoist and such hoist being arranged above and clear of such draft connections so as not to interfere with the operation of the latter.

2. In combination with a tractor having two spaced rearwardly extending frame members, a longitudinally-arranged horizontal power take-off shaft terminating at the rearward end of such tractor and arranged above the horizontal plane of such frame ends and laterally intermediate such frame ends, such shaft being alined with an aperture in the body of the tractor, cover fastening means arranged adjacent such aperture, a draft connection arranged at the rearward edge of such tractor and below the horizontal plane of such frame ends, an auxiliary hoist of the character described mounted upon the rearward end of such tractor, fastened to the latter by such fastening means adjacent the power take-off shaft aperture and to such frame ends, such hoist being arranged above such frame ends the latter supporting the major portion of such hoist, such hoist comprising a frame one element of which is box-like, being open

hoist and such hoist being arranged above and clear of such draft connections so as not to interfere with the operation of the latter.

3. In combination with a tractor provided with an operating station arranged at the rearward end thereof and operating controls grouped immediately forward of such station an auxiliary hoist of the character described mounted upon the rearward end of such tractor and operating controls for such auxiliary hoist being arranged in grouped relation rearwardly of such operating station and operable from the latter.

4. In combination with a tractor provided with an operating station arranged at the rearward end thereof and operating controls grouped immediately forward of such station, an auxiliary hoist of the character described mounted upon the rearward end of such tractor, operating controls for such auxiliary hoist being arranged in grouped relation rearwardly of such operating station and operable from the latter, such hoist comprising a frame closed at the top thereof, such top thus constituting an operating platform for such hoist.

5. In combination with a tractor having two spaced rearwardly extending frame members, a longitudinally-arranged horizontal power take-off shaft terminating at the rearward end of such tractor and arranged above the horizontal plane of such frame ends, such shaft being alined with an aperture in the body of the tractor, cover fastening means arranged adjacent such aperture, an auxiliary hoist of the character described mounted upon the rearward end of such tractor fastened to the latter by such fastening means adjacent the power take-off shaft aperture and to such frame ends, such hoist being arranged above such frame ends the latter supporting the major portion of such hoist, such hoist comprising a frame and a longitudinally-arranged operating stub shaft alined and loosely coupled to such power take-off shaft extending thru and being journaled in the end of such frame.

6. In combination with a tractor having two spaced rearwardly extending frame members, a longitudinally-arranged horizontal power take-off shaft terminating at the rearward end of such tractor and arranged above the horizontal plane of such frame ends, such shaft being alined with an aperture in the body of the tractor, cover fastening means arranged adjacent such aperture, an auxiliary hoist of the character described mounted upon the rearward end of such tractor fastened to the latter by such fastening means adjacent the power take-off shaft aperture and to such frame ends, such hoist being arranged above such frame ends the latter supporting the major portion of such hoist, such hoist comprising a frame one element of which is box-like, being open

at the end facing rearwardly and away from the connection between such hoist and the tractor and a longitudinally-arranged operating stub shaft alined and loosely coupled to such power take-off shaft extending thru the end of such frame element facing the tractor.

7. In combination with a tractor having two spaced rearwardly extending frame members, a longitudinally-arranged horizontal power take-off shaft terminating at the rearward end of such tractor and arranged above the horizontal plane of such frame ends, such shaft being alined with an aperture in the body of the tractor, cover fastening means arranged adjacent such aperture, an auxiliary hoist of the character described mounted upon the rearward end of such tractor fastened to the latter by such fastening means adjacent the power take-off shaft aperture and to such frame ends, such hoist being arranged above such frame ends the latter supporting the major portion of such hoist, such hoist comprising a frame and a longitudinally-arranged operating stub shaft alined and loosely coupled to such power take-off shaft extending thru the end of such frame element facing the tractor, such frame element further provided at the bottom thereof with two flanged feet fastened to such rearwardly-extending frame ends.

8. In combination with a tractor having two spaced rearwardly extending frame members, a longitudinally-arranged horizontal power take-off shaft terminating at the rearward end of such tractor and arranged above the horizontal plane of such frame ends, such shaft being alined with an aperture in the body of the tractor, cover fastening means arranged adjacent such aperture, an auxiliary hoist of the character described mounted upon the rearward end of such tractor fastened to the latter by such fastening means adjacent the power take-off shaft aperture and to such frame ends, such hoist being arranged above such frame ends the latter supporting the major portion of such hoist, such hoist comprising a frame and a longitudinally-arranged operating stub shaft alined and loosely coupled to such power take-off shaft extending thru the end of such frame element facing the tractor, such frame element further provided at the bottom thereof with two flanged feet fastened to such rearwardly-extending frame ends and two spaced frame ends extending rearwardly in spaced relation from such frame element and carrying between them the hoist drums, and driving mechanism for such hoist.

RALPH B. MOORE.
